UNITED STATES PATENT OFFICE.

ORLANDO P. BRIGGS, OF CHICAGO, ILLINOIS.

DESIGN FOR A WATER SPOUT OR CONDUCTOR.

SPECIFICATION forming part of Design No. 16,877, dated August 31, 1886.

Application filed March 30, 1886. Serial No. 197,217. Term of patent 14 years.

To all whom it may concern:

Be it known that I, ORLANDO P. BRIGGS, of Chicago, in the county of Cook and State of Illinois, have invented and produced a new and original Design for Water Spouts or Conductors; and I do hereby declare that the following is a full, clear, and exact description thereof, reference being had to the accompanying drawings, and to the letters of reference marked thereon, which form a part of this specification.

This invention relates to a novel and ornamental design or configuration for rectangular water-spouts or leaders, such as are commonly employed for conducting water from the roof of a house to the ground.

A water spout or conductor is herein shown as illustrating my novel design which is provided, as its main feature of novelty, with convexly-rounded corners and adjacent concave parts or flutes, forming with said curved corners smooth reversed or ogee curves at both sides of each corner, said concave parts being united at the margins of their outwardly-bent parts remote from the said corners by well-defined angular bends with the adjacent portions of the middle parts of the sides of the conductor.

My design also embraces a form of conductor in which the latter is provided with convexly-rounded corners and adjacent concave parts or flutes, as above described, and which is oblong in cross-sectional shape and provided in one of its wider faces with a central raised rib or bead connected at each of its sides with the ogives above referred to by oblique or inclined flat faces, and in its narrower faces with central flat parts joining the inner margins of said ogives, as will hereinafter more fully appear.

In the accompanying drawings, Figure 1 is a perspective view of a piece or section of tubular water spout or conductor embodying my improved design. Fig. 2 is a sectional view of the same.

In said drawings, A indicates the spout or conductor, which is rectangular in cross-sectional form, and is made with rounded corners B and adjacent concave parts C, made to form continuous curves with the rounded parts or corners B, so that said parts B and C together form smooth reversed curves or ogives. The

spout is of oblong form, and at its narrower sides the adjacent margins of the concaved parts or flutes C are connected by flat faces D, which are united with the outwardly bent or deflected parts of the flutes C by means of angular bends d. As herein shown, the spout is provided with a flat part or face, E, connecting the flutes C at one of the wider sides of the spout, said face being connected with the said flutes by angular bends e, as shown. At the side of the spout opposite the flat face E is formed a central projecting curved part or bead, F, the side margins of which terminate in a plane located inside of the general plane of the face of the spout, and said curved part or bead F is connected with the adjacent margins of the flutes C at both sides of it by means of flat oblique faces G, making well-defined angles f and g with the said flutes C and with the said curved part or bead F.

I claim as my invention—

1. The design for a rectangular waterspout or conductor herein shown, in which said spout or conductor is provided with convexly-rounded corners and adjacent concave parts or flutes, which form with said rounded corners smooth reversed or ogee curves at each side of said corners, said concave parts or flutes being connected with the middle parts of the sides of the spout or conductor by angular bends.

2. The design for a rectangular water spout or conductor herein shown, in which the latter is narrower in one direction than in the other, and provided with convex rounded corners and adjacent flutes or concave parts, forming with the said rounded corners smooth reversed or ogee curves at both sides of each of said corners, and having in one of its wider faces or sides a convex rib or bead connected with the adjacent ogives by oblique faces, and at its narrower faces or sides flat surfaces between and joining said ogives.

In testimony that I claim the foregoing as my invention I affix my signature in presence of two witnesses.

ORLANDO P. BRIGGS.
